UNITED STATES PATENT OFFICE

126,054

DESIGN FOR A SHIP CLOCK

Robert D. Schoenbrod, Chicago, Ill., assignor to
American Supercraft Corporation, Chicago, Ill.,
a corporation of Illinois

Application September 7, 1940, Serial No. 94,853

Term of patent 7 years

To all whom it may concern:

Be it known that I, Robert D. Schoenbrod, a citizen of the United States of America, residing at 711 West Lake Street, Chicago, Illinois, have invented a new, original, and ornamental design for a Ship Clock, of which the following is a specification, reference being had to the accompanying drawing, forming a part thereof.

Fig. 1 is a front view of a ship clock showing my new design, and Fig. 2 is a side view of the same.

I claim:

The ornamental design for a ship clock, substantially as shown.

ROBERT D. SCHOENBROD.
